UNITED STATES PATENT OFFICE

125,553

DESIGN FOR A DRESS ENSEMBLE

Hanna W. Snyder, Riverside, Conn.

Application January 6, 1941, Serial No. 97,828

Term of patent 3½ years

To all whom it may concern:

Be it known that I, Hanna W. Snyder, a citizen of the United States, residing at Hendrie Avenue, Riverside, in the county of Fairfield and State of Connecticut, have invented a new, original, and ornamental Design for a Dress Ensemble, of which the following is a specification, reference being had to the accompanying drawings, forming part thereof.

I claim:

The ornamental design for a dress ensemble, substantially as shown.

HANNA W. SNYDER.
